UNITED STATES PATENT OFFICE.

ALBERT H. GRAVES, OF EVANSTON, ILLINOIS; EMMA L. GRAVES EXECUTRIX OF THE ESTATE OF SAID ALBERT H. GRAVES, DECEASED.

CONCEALED SUSPENDERS.

1,398,962.

Specification of Letters Patent.

Patented Dec. 6, 1921.

Application filed June 7, 1917, Serial No. 173,287. Renewed July 29, 1921. Serial No. 488,451.

To all whom it may concern:

Be it known that I, ALBERT H. GRAVES, a citizen of the United States, residing at Evanston, in the county of Cook and State 5 of Illinois, have invented certain new and useful Improvements in Concealed Suspenders, of which the following is a specification.

This invention relates to improvements in 10 concealed suspenders, and it has for its salient objects to provide a construction which is extremely convenient in the matter of manipulation in casting off and coupling up; to provide a construction which produces a 15 girding effect around the waistband of the trousers and thus avoids the uncomfortable feeling incident to wearing trousers which are neither supported nor belted at the rear of the waistband; to provide a construction 20 in which the hangers of the suspenders are anchored to the shirt so that the underneath parts of the suspenders remain in definitely adjusted position and do not lose their adjustment when the waistband attachments 25 are cast off; to provide a construction which may be conveniently adjusted to suitable waistband girth and to accomplish this end without leaving loose ends; to provide a construction having waistband attachments 30 which may be quickly and conveniently transferred from one pair of trousers to another; and in general, to provide an improved article of the character referred to.

The invention consists in the matters hereinafter described, and more particularly pointed out in the appended claims.

In the drawing—

Figure 1 is a perspective view showing the suspenders in place upon a person;

Fig. 2 shows the upper part of a pair of trousers spread open so as to show the inside of the waistband and with the waistband attachments applied thereto and coupled to the suspender hangers;

Fig. 3 is an inside elevation of a reeving support forming one feature of the suspenders;

Fig. 4 is a side elevation of the same;

Fig. 5 is a detail of a take-up device;

Figs. 6 and 7 are front and side elevations, respectively, of a preferred form of cast-off coupling.

There is upon the market, and in use to a limited extent, a type of concealed suspenders in which shoulder or suspender

straps 1 are connected together approximately between the shoulder blades, as indicated at 2, extend thence up over the shoulders and part way down the front, and attach at the latter point to hanger straps 3 which 60 carry wire button loops 4, and which hanger straps are continued from the point of attachment with said button loops upwardly and rearwardly to points of connection 5 with back straps 6, which latter are also connected at the back between the shoulder blades. This type of suspenders thus provides but a single support at each side; the button loops being buttoned upon the two side suspender buttons of the trousers, and 65 the trousers left unsupported throughout the front and rear halves of the waistband. My invention combines with suspenders of this general type, supplementary features which effectively support the trousers at 70 additional points; at the same time produces a girding or belting effect which draws the waistband snugly around the wearer, and furthermore brings the cast-off coupling in effect to the outside of the shirt, so that the 75 trousers may be cast-off and coupled on instantly and with the greatest convenience.

Describing these features as embodied in the preferred construction shown, 7, 7, designate two girding strands which, as herein 80 shown, take the form of cords, but may be of bands or strap-like construction. Each strand is provided at one end with a button-loop 8, and at its opposite end is returned upon itself to form a button-loop 9, the 85 return end carrying a take-up clip 10 which may be adjusted to vary the length of the strand. The intermediate part of each strand is trained through a reeving support 11, taking the form in the present instance 90 of a wire ring doubled over upon itself to provide a central downwardly extending loop 12, two lateral upwardly extending loops 13, 13, and a handle extension 14. The loop 12 and the handle extension 14 lie 95 in parallel planes; the loop 12 being adapted to embrace the shank of a suspender button and lie next to the button while the handle extension 14 lies back against the inside of the trousers waistband. The loops 13 stand 100 at right angles to the plane of the loop 12 and form in effect eyes through which the strand 7 renders. The eye loops 13 are spaced far enough apart so that the strand 105 may be drawn out between them while ap- 110

plied to the button, by simply drawing the support, 11, bodily downward far enough to detach the reeveing support from the button. The strand is drawn into the same shape to apply it to the button. The take-up device 10 comprises two members, viz: a tubular clip 15 clamped upon the end of the cord and provided at its end with pivot cheeks 16 and a biting projection or jaw 17. The 10 second member 18 is of trough-like construction adapted to accommodate loosely the cord, provided with pivot ears 19 and pivot projections 20 engaged with the cheeks 17; the relation between the two members being 15 such that when they are brought into parallel relation the point of the jaw 17 bites into the cord lying in the member 18 and locks it against sliding movement.

Instead of the wire button loop commonly 20 used heretofore on suspenders of this general type, I use a loop which provides a headed hook-like support, as best shown in Figs. 6 and 7. That is to say, the sides of the loop 4 are brought together and bent to form a 25 hook 4', the upturned end portion of which hook takes the form of a triangular head or loop 4''. This head is to be buttoned through a suitable buttonhole 21 in the shirt so as to expose the hook at the outside, and 30 the enlarged head with its shoulders 4''' serves to anchor the suspender hanger reliably to the shirt at this point. That part of the girding strand lying between the reeveing support and the front suspender button 35 is hooked over the hook and is, of course, free to slide upon the latter. The peculiar arrangement of the supporting straps and hangers of suspenders of this type produces a suspension draft not vertically upward 40 but obliquely from the side button upwardly and rearwardly. This results in producing a girding effect as regards the front half of the trousers. The fact that the girding strands extend from the cast-off hooks down 45 through the reeveing supports through which they are free to slide or render insures a pursing effect as to the rear halves of the waistband, thus insuring that the trousers shall not only fit snugly at the waist but 50 shall produce a trig, comfortable feeling on the part of the wearer.

The girding attachments may remain on the trousers from day to day, while the remainder of the suspenders remains with 55 the shirt.

The facility with which the suspenders may be cast off by simply lifting the girding strands out of the hooks 4 is obvious. When the girding strands are adjusted to 60 proper length *i. e.*, to a length almost exactly equal to the distance between the front and back buttons of the trousers, the strands will be almost completely concealed while being worn. The advantage of having the 65 suspender hangers anchored and attached to

a precise definite point, so that the wearer need not fumble around to find a detached hanger end, as is necessary with the old type of concealed suspenders, is obvious. The fact that the wearer is assured of always 70 having his shirt body so attached that the proper blouse effect is produced and that there is no danger of tearing by bringing the weight of the trousers upon the side body of the shirt is also an obvious ad- 75 vantage.

The constructions shown and described constitute a preferred embodiment of my invention, but the claims are not to be understood as limited to these details, except in 80 so far as they are made specific thereto.

I claim as my invention:

1. In concealed suspenders, the combination with shoulder straps provided with cast-off hangers constructed to button to the shirt 85 and reliably anchor said straps thereto, as well while the trousers-supports are cast off and while connected to said cast-offs, of a girding strand attachable to the trousers in front and rear waistband regions, respectively, reeveing supports attachable to the waistband and at intermediate points and through which said girding strand renders, and means for coupling intermediate parts 90 of said strand to the corresponding cast-off 95 hangers.

2. In concealed suspenders, the combination with shoulder straps, provided with button-headed cast-off hangers constructed to button through the shirt and reliably anchor 100 said straps thereto, as well while the trousers-supports are cast off and while connected to said cast-offs, of flexible girding strands, one for each side, each adapted to be attached at the front and rear of the trousers waistband, reeveing supports attachable to the trousers waistband at the sides of the trousers and through which said girding strands 105 respectively render, and means for coupling an intermediate part of each girding strand 110 to the corresponding cast-off.

3. In suspenders, the combination of shoulder straps adapted to be worn under the shirt and provided with cast-off hangers located approximately above the hips, of a 115 waistband attachment consisting of a strand adapted to be buttoned to the waistband at the front and rear regions thereof, and means for detachably coupling the intermediate part of said strand to the corresponding cast-off hanger, through the shirt.

4. In suspenders, the combination of shoulder straps adapted to be worn under the shirt and provided with cast-off hangers located one at each side approximately above 125 the hips, of a waistband girding attachment consisting of a strand adapted to be buttoned to the waistband at the front and rear regions thereof, a pair of reeveing attachments adapted to be secured to the waistband ap- 130

proximately above the respective hips and through which attachments said girding strand extends, and means for detachably coupling the parts of said girding strand adjacent to said reeving attachments to the corresponding cast-off hangers, through the shirt.

5. In suspenders, the combination of shoulder straps adapted to be worn under the shirt and provided with cast-off hangers located approximately above the respective hips, of waistband girding attachments, one at each side, each consisting of a strand adapted to be buttoned to the waistband at 10 the front and rear regions thereof, and take-up mechanism for adjusting the length of each girding strand, a reeving attachment adapted to be secured to the waistband approximately above the hip, one at each side, 15 and through which said girding strands respectively extend, and coupling devices for connecting the respective hangers with the corresponding girding strands, said coupling devices serving normally to anchor the suspender hangers to the shirt.

6. In suspenders, the combination of shoulder straps adapted to be worn under the shirt and provided with cast-off hangers located approximately above the hips, a cast-off coupling upon each hanger constructed to provide a supporting projection exterior to the shirt and to anchor the hanger to the shirt, girding waistband strands, one for each side, each adapted to be attached to the 30 front and rear waistband buttons of the trousers, a reeving support at each side, adapted to be attached to the corresponding side button of the trousers and through which support the girding strand extends, 35 the intermediate portion of said strand adjacent to the reeving support being adapted to be detachably connected to the projection of the cast-off coupling.

7. In suspenders, the combination of shoulder straps adapted to be worn under the shirt and provided with cast-off hangers located approximately above the hips, a cast-off coupling upon each hanger embodying a hook adapted to be buttoned through an opening in the shirt, girding waistband 45 strands, one at each side, each adapted to be buttoned to the front suspender button and to the rear suspender button of the trousers and each provided with a take-up mechanism for adjusting the length of the strand, 50 a reeving support at each side, adapted to be adjustably connected to the corresponding side suspender button of the trousers and through which support the corresponding girding strand extends, the intermediate portion 55 of said strand being adapted to be hooked upon the corresponding cast-off coupling.

8. In suspenders, a reeving support formed of wire comprising a central downwardly extending loop adapted to embrace the shank of a button, two lateral upwardly extending loops through which a strand may render, and a handle extension extending far enough below the bottom of the central loop 60 to be accessible when the loop is applied to the button.

9. In suspenders, a reeving support formed of wire comprising a central downwardly extending loop adapted to embrace 65 the shank of a button, two lateral upwardly extending loops through which a strand may render, and a handle extension extending substantially below the bottom of said central loop, the upper ends of said 70 lateral loops being spaced away from each other and arranged to lie in parallel planes substantially at right angles to the plane of said central loop.

ALBERT H. GRAVES.
